[57] **ABSTRACT**

A cylindrical brush having bristles located in a helical column upon the surface of the cylinder and a pulley fastened at the base of the cylinder with a cord passing through the grooved rim of the pulley. The brush is adjustably mounted on a plate having suction cups on the side of the plate opposite the brush. The suction cups secure the plate to a shower wall and the brush is adjusted to the desired height of a body portion of a person. The body portion is washed and massaged when it is maintained in contact with the brush and the cord is reciprocated by the person to produce a reciprocating rotation of the brush.

THERAPEUTIC BATH BACK BRUSH AND PROCESS OF USING SAME

BACKGROUND OF THE INVENTION

1. Field of the Invention

This invention relates to brushes and specifically to mechanically rotated brushes.

2. Description of the Prior Art

Brushes of many descriptions exist. Brushes which are usable in a wet environment, such as in a shower, are limited generally to those brushes which are hand held or passive. For safety reasons electrically operated brushes are not usable in a shower. The hand held brushes adapted to clean the back of a person are relatively difficult to manipulate. Passive brushes which require movement of a portion of the body in contact with the brush are undesirable for cleaning and massaging purposes.

The present invention provides a safe mechanically operated brush which satisfactorily cleans and massages and is suited to use in a shower. By providing a cylindrical brush having bristles helically formed on the cylinder and a cord and pulley operatively connected to the brush, the brush can be rotated readily by reciprocating the cord and pulley. Reciprocating rotation of the brush will produce an efficient motion of the bristles upon the contacting body portion.

SUMMARY OF THE INVENTION

Briefly, this invention provides a back brush for cleaning and massaging a portion of the body of a person. The brush comprises a rotatable brush with means connected thereto for mounting the brush upon a support surface. A pulley is mounted upon the brush and a cord is located within the grooved rim of the pulley to reciprocatably rotate the pulley and brush as the cord is pulled over the pulley.

BRIEF DESCRIPTION OF THE DRAWING

In the drawing:

The FIGURE is a perspective view of an embodiment of the present invention.

DESCRIPTION OF THE PREFERRED EMBODIMENT

Referring now to the drawing, the figure shows a preferred embodiment of the back brush. The back brush 10 comprises a rotatable brush 11 having a pulley 12 mounted thereon with a cord 13 located within the grooved rim of the pulley. Preferably, pulley 12 is mounted at one end of brush 11. Means 14 are provided for mounting the brush 11 upon a support surface (not shown) such as a wall. The mounting means comprises two support collars 15 located substantially at the ends of brush 11, a base plate 16 with two columns of hooks 17 mounted on one side of the base plate, and a plurality of suction cups 18 on the side of the base plate opposite the hooks. Collars 15 are substantially rigid to provide firm support for brush 11. Each collar is looped around brush 11 providing a track within which

the brush can freely rotate. Two legs 20 of each collar 15 extend away from the looped collar portion and an eyelet 21 is formed at the end of each leg 20. Each eyelet engages a corresponding hook 17. The position of brush 11 can be adjusted by relocating the eyelets on different hooks. It is apparent that other conventional mounting means can be substituted for that specific means 14 illustrated. This invention does not intend to limit the means to that specific embodiment shown. Brush 11 may be cylindrical in shape and have at least one column of bristles 24 formed along the outside surface of the cylinder. More columns of bristles may be added.

According to the operation of the brush 10, the base plate 16 is placed on a supporting surface wall such as in a shower. The plate is secured to the wall on suction cups 18. Brush 11 is adjusted to the proper height to wash the desired body portion of the bather by locating eyelets 21 on appropriate hooks 17. The bather grasps cord 13 at its ends and pulls the cord back and forth. The reciprocating motion of the cord, reciprocates pulley 12 and brush 11. The bather moves into contact with the bristles 24 and continues to pull on the cord. The helical bristles will clean and massage the contacting body portion and provide a force in two directions, horizontal and vertical.

I claim:

1. A back brush for cleaning and massaging a portion of the body of a person, which comprises:
30 a rotatable brush comprising a cylinder with the bristles located in a helical column upon the outer surface of the cylinder;
means for mounting the brush upon a support surface;
35 a pulley mounted upon the brush; and
a cord located within the grooved rim of the pulley to reciprocatably rotate the pulley and brush.
2. A back brush as recited in claim 1 wherein the pulley and cord are located at the lower end of the cylinder to facilitate manual reciprocation with the brush vertically positioned at a height which substantially locates the cord and pulley at the normally hanging position of the arms of the person.
3. A back brush as recited in claim 1 wherein the pulley and cord are completely exposed and the cylinder is sealed at its ends.
4. A back brush as recited in claim 3 wherein the means for mounting comprises:
50 a base;
means for adjustably attaching the brush to the base;
and
suction cups mounted on the base to secure the base to a wall.
5. A process for cleaning and massaging a portion of the body of a person comprising the steps of:
55 reciprocating a connecting cord and pulley;
rotating a brush having a helical column of bristles simultaneously with the step of reciprocating; and
placing the body portion in contact with the rotating helical brush.
